Primary Examiner — Prabhakar G Deshmukh*(74) Attorney, Agent, or Firm* — Standley Law Group LLP(57) **CLAIM**

The ornamental design for a weighing utensil, as shown and described.

DESCRIPTION

FIG. 1 is a top front perspective view of the weighing utensil;

FIG. 2 is a right side elevation view thereof, the left side elevation view being a mirror image thereof;

FIG. 3 is a top plan view thereof;

FIG. 4 is a bottom plan view thereof;

FIG. 5 is a rear elevation view thereof;

FIG. 6 is a front elevation view thereof; and,

FIG. 7 is a side elevational view of a graduated flask with the weighing utensil inserted in a neck thereof, for environmental purposes.

The broken lines in FIG. 7 illustrate environment and forms no part of the claimed design.

1 Claim, 3 Drawing Sheets(56)
